UNITED STATES PATENT OFFICE.

GEORGES BARAULT, OF BRUSSELS, BELGIUM.

HEATING STOVE.

Application filed July 25, 1924. Serial No. 728,206.

To all whom it may concern:

Be it known that GEORGES BARAULT, a citizen of the French Republic, residing at Brussels, Rue de Hennin 83, in the Kingdom of Belgium, has invented certain new and useful Improvements in Heating Stoves, of which the following is a specification.

My invention relates to heating stoves as used for domestic purposes, of the kind in which the draught takes place immediately above the fire-box without passing through the fuel stored in a fuel chamber arranged in the upper part of the stove above the fire-box.

One object of my invention is to provide new and improved means to secure the complete combustion of the combustion products at their escape from the fire-box and to recover the heat resulting from the said combustion.

A further object consists in providing means adapted to bring to the combustion products in ignition the gases and volatile matters which may be eventually distilled from the fuel contained in the fuel chamber, so as to have the benefit of the combustion of the said matters. And a still further object consists in so arranging the air inlets to the fire-box and to the products in combustion that a complete combustion will be obtained at the escape of the combustion products from the fire-box even if the combustion in the fire-box is reduced to a minimum.

With these objects in view my invention essentially consists in special arrangements and combinations of parts, as will be hereinafter fully described and pointed out in the appended claims.

Referring to the annexed drawings which show as an example one embodiment of my invention:

Fig. 1 is a front elevation of the whole heating stove.

Fig. 2 is a vertical section taken on line A—B in Fig. 1.

Fig. 3 shows a horizontal section taken on line C—D in Fig. 2.

Fig. 4 shows a horizontal section taken on line E—F in Fig. 2 giving a top view of a movable grate.

Fig. 5 shows a part of a horizontal section corresponding to Fig. 4 the movable grate being in another position.

As shown in Figs. 1 and 2 the heating stove comprises a fire-box 1 provided on

the outside with vertical heat radiating wings 2. The said fire-box which is designed to contain the fuel in ignition rests upon a base 3 which is provided with a door 4 and in which a movable ash-pan 5 is placed. The fire-box 1 is fitted in its front face with a fixed grate 6 which is designed to retain the fuel and in front of which a door 7 is provided this door having a number of apertures which are closed by mica-plates or the like as usually. The door 7 is provided at the lower part with air inlets 9 which are controlled by a slide 10 moved by a lever 11.

On the fire-box 1 the upper body 12 is placed forming a fuel chamber 13 which is closed at the rear by a movable wall 14 which is slidden between guides 15 and 16 projecting from the lateral walls of the body 12. This movable wall rests upon a plate 17 of refractory material which fits into a support 18 formed by ribs projecting from the lateral walls of the fire-box 1.

The fuel chamber 12 is connected at the rear, at a distance from the movable wall 14, to a heat recuperating device the wall 19 of which extends above the fire-box 1 near the lower edge of the plate 17. The wall 19 which is connected at 20 (Fig. 3) to the lateral walls of the body 12 is in one piece with lateral heat radiating wings 21 forming the chamber 22 of the heat recuperating device which is closed at the rear by a plate 23 provided with external heat radiating wings 24 and with similar internal wings 25. The plate 23 carries a flue opening 26 which is connected to the usual chimney.

In the chamber 22 of the recuperating device a number of tubes 27 are arranged the said tubes being slightly inclined and opening at the lower end of the recuperating device at 28, outside the rear part of the fire-box 1 and at the upper part at 29 under an aperture 30 of the upper plate or cover 31 of the heating stove. This aperture 30 is preferably provided with a perforated metal sheet or with wire-gauze. The upper plate 31 is provided with a charging opening 32 closed by a cover 33 and rests, in the front face of the heating stove, on a flange 34 of the body 12. The upper plate 31 is further provided with an aperture 35 which is suitably protected by a perforated metal sheet 36 behind which is placed a light flap 37 (Fig. 2) formed by a thin metal sheet

which is freely suspended at its upper edge so as to be able to adjust itself automatically.

in a suitable opened position according to the intensity of the draught in the upper part of the body 12.

The fire-box 1 is provided at its lower end with a fuel supporting plate 38 having an aperture 39 under which slides a closing plate 40 fitted with an operating rod 41 projecting outside the fire-box. An inclined grate 42 rests on the fuel supporting plate 38 and is provided with a number of fixed bars 43 between which movable bars 44 are adapted to be displaced longitudinally.

In the example of the drawing two movable bars 44 have been shown the said bars being connected by two cross-pieces 45 to one of which a rod 46 is fixed, the said rod ending in a ring 47 in which the end of a lever 48 is engaged which lever is pivotally mounted on a support 49.

20 The fixed bars 43 and also the movable bars 44 have a zigzag shape as shown in Fig. 4 in such a manner that when the movable bars are displaced by aid of lever 48 so as to be brought for instance from the position shown in Fig. 4 into the position shown in Fig. 5 the space between the fixed and the movable bars will be modified in shape giving raise to lozenge shaped openings through which the ashes can easily pass into the ash-pan 5. When the movable bars are returned in their initial position (Fig. 4) on the contrary, the ashes of relatively great dimensions are crushed between the fixed and movable bars.

25 In the lower rear-part of the fire-box below the inclined grate 43 there is provided an aperture 50 acting as it will be explained hereinafter as a permanent air inlet.

When the heating stove is operating normally, the fuel chamber 13 is filled up with fuel whilst the fuel contained in the fire-box 1 is in ignition. If the air-inlets 9 are closed by the slide 10, only a small portion of the fuel supported by the inclined grate 42 is maintained at incandescence by a constant quantity of air passing through aperture 50 and through the fuel under the suction resulting from the draught and acting in the space 51 at the base of the heat recuperating device. If then the inlet apertures 9 are opened gradually, the intensity of the combustion increases in the fire-box 1 in the part adjacent to the grate 6. The draught acting also in the space between the walls 19 and 14, air is also admitted through the automatic flap 37. This current of air carries with it the gases and volatile matters which are eventually liberated in the fuel chamber 13; the mixture or the air alone as the case may be, passes at 52 above the wall 14, descending between the walls 19 and 14 in the direction of the arrow 53 so as to reach finally the space or chamber 51 at the base of the heat recuperating device, thus bringing to this point the neces-

sary quantity of air to secure the complete combustion of the gases and of the carbon monoxide resulting from the combustion in the fire-pot 1 and which are carried to the igniting temperature on account of the inclination of the grate 42 and of the permanent air inlet 50. As a result a very intensive combustion takes place at 51; the flames ascend in the heat recuperating device 22 thus heating the walls of the said device and also the tubes 27 in which the air is caused to circulate the cold air contained in the place or room which is to be heated entering the tubes 27 at the lower end 28 and escaping at the upper end 29 into the place or room after having recovered the heat contained in chamber 22 and a part of this heat is further radiated in the room through the wings 21 and 24 of the heat recuperating device.

If, on the contrary the apertures 9 are closed to moderate the working of the stove, the suction of air resulting from the draught of the chimney causes the flap 37 to open to a greater extent as previously in such a manner that the said flap always secures automatically the inlet of the quantity of air which is necessary to obtain a complete combustion the said quantity of air being in fact invertedly proportional to the quantity of air admitted through the controlled apertures 9.

It will be observed that as a result of the above described construction, the carbon monoxide and also the volatile matters escaping eventually from the charge of fuel contained in the chamber 13, together with the gases resulting from the combustion in the fire-box 1 will be burnt at the lower end 51 of the heat recuperating device, this end 51 acting as a combustion chamber to achieve the combustion. In fact it is in this chamber that the combustion is the most intensive and it is in order to resist to the high temperature at this point that the plate 17 is made of a high refractory material. When the combustion is moderated by the closure of the air inlet 9, the rear part of the fuel supported by the grate 42 is nevertheless maintained at incandescence by the permanent air inlet taking place through the aperture 50; although the quantity of air admitted through this aperture is reduced to the minimum, the complete combustion of the gases escaping from the fire-box is nevertheless secured by a greater quantity of air which is then admitted through the automatic flap 37, this quantity being as already stated always invertedly proportional to the quantity of air admitted through the controlled air inlets 9.

The removing of the ashes from the fire-box 1 is very easily obtained by the displacement as described of the movable part of the inclined grate 42 and further by the dis-

placement of the plate 40 closing normally the aperture 39 provided in the supporting plate 38.

What I claim is:

5. 1. In a heating stove a fire-box, the said fire-box being provided with controlled air-inlets and with a permanent air-inlet, a grate in the said fire-box, a fuel chamber arranged above the fire-box, means for admitting air 10 above the fuel chamber, a high recuperating device arranged at the rear of the fuel chamber the said device being provided with a draught connection and being separated from the fuel chamber by an air passage, 15 whereby the air admitted above the fuel chamber is conducted at the upper rear end of the fire-box to achieve the combustion of the gases escaping from the fire-box at the lower end of the heat recuperating device.
20. 2. In a heating stove, a fire-box, the said fire-box being provided with controlled air inlets, a grate arranged in the said fire-box, means for admitting permanently a reduced quantity of air below the said grate, a fuel chamber arranged above the fire-box, means for admitting air automatically above the fuel chamber, a heat recuperating device arranged at the rear of the fuel chamber, a movable wall arranged in the fuel chamber 25 at a distance from the heat recuperating device, whereby a passage is formed between the fuel chamber and the heat recuperating device to conduct the air admitted above the fire-box to the upper rear-end of the fire-box and to the lower end of the heat recuperating device and a combustion chamber formed at the lower end of the heat recuperating device above the upper rear end of the fire-box.
30. 3. In a heating stove, a fire-box, the said fire box being provided with controlled air inlets, a fuel supporting plate arranged in the said fire-box, an inclined grate adjacent to the said supporting plate, means for admitting permanently a reduced quantity of air below the inclined grate, a fuel chamber arranged above the fire-box, a heat recuperating device arranged at the rear of the fuel chamber the said device having a wall closing 35 the fuel chamber, a movable wall arranged in the fuel chamber at a distance from the said wall of the heat recuperating device, whereby an air passage is formed between the fuel chamber and the heat recuperating device, a combustion chamber formed at the upper rear-end of the fire-box between the lower end of the heat recuperating device and the movable plate of the fuel chamber, plate or cover closing the fuel 40 chamber at its upper end, the said plate being provided with an air inlet, and a freely suspended flap cooperating with the said air inlet whereby the quantity of air admitted above the fuel chamber under the action of the draught is invertedly proportional to the quantity of air admitted to the fire-box through the controlled air inlets.
4. In a heating stove, a fire-box, the said fire-box being provided with controlled air inlets, a fuel supporting plate arranged in the said fire-box, the said plate having an aperture and a movable slide closing normally the said aperture, an inclined grate adjacent to the said supporting plate, the said grate comprising fixed iron-bars and movable iron-bars of zig-zag shape, means for admitting permanently a reduced quantity of air below the said inclined grate, a fuel chamber arranged above the fire-box, a refractory plate located in the said fuel chamber at a distance from the upper part of the fire-box, a wall resting upon the said refractory plate whereby a descending air passage is formed in the fuel chamber, a heat recuperating device fixed to the fuel 50 chamber, the said device being open at its lower part above the fire-box and having a wall ending above the fire-box at a level higher than the refractory plate, whereby a combustion chamber is formed above the upper rear-end of the fire-box a plate or cover closing the fuel chamber at its upper end the said plate being provided with an air inlet, and a freely suspended flap cooperating with the said air inlet whereby the quantity of air admitted above the fuel chamber under the action of the draught is invertedly proportional to the quantity of air admitted to the fire-box through the controlled air inlets.
5. In a heating stove a supporting base, a fire-box, the said fire-box being provided with controlled air-inlets, a fuel supporting plate arranged in the said fire-box, the said plate having an aperture and a movable slide closing normally the said aperture, an inclined grate adjacent to the said supporting plate, the said grate comprising fixed iron-bars and movable iron-bars, of zig-zag shape and being located above an air inlet aperture provided in the fire-box and a body resting upon the fire-box, the said body comprising an upper air inlet, a descending air passage, a fuel chamber and a heat recuperating device forming a chamber having heat radiating wings and air circulating tubes.
6. In a heating stove, a fire-box provided with controlled air inlets and a separate permanent air inlet and a body located above the fire-box, the said body comprising a fuel chamber a heat recuperating device, and a descending air passage arranged between the fuel chamber and the heat recuperating device, the said air passage and heat recuperating device forming above the upper rear end of the fire-box a combustion chamber for the gases escaping from the fire-box.

In testimony whereof I have affixed my signature.

GEORGES BARAULT.
